UNITED STATES PATENT OFFICE.

JOHN A. HEBB, OF UNIONTOWN, PENNSYLVANIA, ASSIGNOR TO THE HEBB COKE DRAWER COMPANY, OF UNIONTOWN, PENNSYLVANIA.

COKE-DRAWING MACHINE.

SPECIFICATION forming part of Letters Patent No. 727,942, dated May 12, 1903.

Application filed August 14, 1902. Serial No. 119,617. (No model.)

To all whom it may concern:

Be it known that I, JOHN A. HEBB, a citizen of the United States, residing at Uniontown, in the county of Fayette and State of Pennsylvania, have invented certain new and useful improvements in Coke-Drawing Machines, of which the following is a specification, reference being had therein to the accompanying drawings, forming part of this specification, in which—

Figure 1 is a plan view of my improved coke-drawing machine, showing it in position in front of an oven-door, portions of the conveying mechanism and the beam being broken out. Fig. 2 is a vertical longitudinal section on the line II II of Fig. 1 on an enlarged scale. Fig. 3 is a similar view at right angles to Fig. 2, indicated by the line III III of Fig. 1. Fig. 4 is a detail view of the vertical clutch mechanism of Fig. 3 and its operating-lever at right angles to said figure. Fig. 5 is a horizontal plan view of the under supporting-framework and the mechanism thereon, partially shown in section and indicated by the line V V of Fig. 3. Fig. 6 is a vertical sectional view of the machine on the line VI VI of Fig. 5, showing the traction-driving and clutch-operating mechanism. Figs. 7 and 8 are detail sectional views indicated by the lines VII VII and VIII VIII of Fig. 1, illustrating the means for rotating the turn-table. Fig. 9 is a vertical section on the line IX IX of Fig. 2.

My invention relates to apparatus for drawing coke from the oven; and it consists of a traveling structure or framework provided with supporting-wheels adapted to travel by traction upon supporting-rails laid in front of a bank of ovens, such framework supporting a conveying mechanism for carrying away the coke drawn from the oven, a rotatable table, a rake-beam mounted on the table, together with gearing for raising and lowering the beam and for giving it longitudinal movement in either direction, gearing for rotating the table, clutch mechanism and levers rotatably mounted on the framework, together with the various other operative elements and details of construction, as shall be more fully hereinafter set forth.

Related subject-matter is embodied in sep-

arate applications bearing the Serial Nos. 119,618, 119,619, and 119,620, filed August 14, 1902; No. 120,559, filed August 21, 1902, and No. 125,644, filed October 2, 1902.

Referring now to the drawings, A represents the foundation-framework of a portable carriage upon which is supported for the purpose of providing lateral range a turn-table B, upon which is carried the various operative and manipulative portions of the machine, with the exception of the conveyors, main shaft, traction driving-gear, and the prime mover. The turn-table B is supported upon casters or rollers 2, mounted in bearings in framework A, the turn-table being provided with a circular track 3 of any suitable design or construction, but preferably grooved, so as to assist in maintaining the turn-table in a central position.

4 is the main shaft, mounted in suitable bearings in the main framework and driven at its end by an engine or motor, which may also conveniently be a compressed-air or electric motor.

Extending at right angles to shaft 4 and on substantially the same level is a shaft 5, and centrally arranged at the middle of the turn-table is a vertical shaft 6, the lower end of which rests in a step-box 7 in the main framework A and which is preferably provided with a row of ball-bearings 8 to reduce friction.

Mounted on shaft 6 is a bevel-pinion 9 in driving engagement with a smaller bevel-wheel 10 on shaft 4, while wheel 9 meshes into a similar wheel 11 on shaft 5, and as thus connected when main shaft 4 is driven the shafts 5 and 6 will be also continuously driven, shaft 6 operating at a somewhat slower rate of speed. From these main shafts all of the various operations of the machine are transmitted through the gearing, clutch, and lever mechanism, hereinafter described.

The turn-table B is rotated in either direction by a hand-wheel crank 12, connected to a shaft 13, mounted in support 14 and provided with a bevel-pinion 15 in engagement with bevel 16 on the upper end of the shaft 17, which extends downwardly through the turn-table. A circular rack 18 is mounted upon the upper face of framework A, into which gears pinion 19, mounted on a shaft carried

in bearings on the under side of the turn-table and provided with a worm-wheel 20. The worm 21, secured to the lower end of shaft 17, meshes into worm-wheel 20, and by this construction the turn-table may be rotated in either direction through the crank and gearing at the upper end of the vertical shaft.

The beam-supporting and beam-manipulating framework consists of two main standards 22 at each side of central shaft 6, which standards are secured to the upper side of the turn-table and are provided at their upper portion with pillow-blocks or bearings 23, in which is mounted the cross-shaft 24, provided at its middle portion centrally above the center of the machine with driving-pinions 25 in driving engagement with racks 26, secured to each side of the beam 27, the central web of which extends between pinions 25 and rests upon a roller 28, journaled on shaft 24, by which the weight of the beam is carried and the teeth relieved from the strain of gravity. Above the beam is a roller 29, connected by links 30 to shaft 24, which roller 25 provides an upper bearing for the beam and holds it in engagement with the driving-pinions. The forward end of the beam is provided with a pivotally-attached rake-head 31, adapted to fold backwardly on coming into contact with the coke in entering the oven and to be automatically extended by tension of a spring 32 at the back end of the beam and connected with the upwardly-extending arms 34 of the rake-head by rod 33, passed through slot 35.

On each side of the beam, freely journaled on shaft 24, are the conical friction-drums 36, provided on their inner portions with peripheral beveled teeth 37, the teeth of both of such drums being in constant engagement with a driving bevel gear-wheel 38, secured to the upper end of the shaft 6, by which both friction-drums are constantly driven in opposite directions. The hub of each drum bears against a collar 39, secured to shaft 24, by which the drums are held in mesh with wheel 38.

Beyond the friction-drums on each side is a surrounding friction-sleeve 40, each of which is provided with a hub portion in driving engagement with the shaft 24 by a spline or key 41, so that when either of such sleeves is brought into frictional engagement with its drum by shifting the sleeve upon the drum it will transmit movement to shaft 24 in one direction or the other, according to which drum 36 is utilized. The shifting operation is secured through lever 42, pivoted at 43 and connected at 44 to a shifting bar 45, mounted in suitable bearings on the uprights 22 and provided with forks 46, engaging collars or flanges on the hub of sleeve 40, as clearly shown in Figs. 1 and 3. By this construction when the lever 42 is shifted in either direction but one of the friction-clutches will be engaged, and by adjusting the sleeves 46 so that in their intermediate

position they are just clear of the friction-drums the necessary movement of lever 42 is reduced to a minimum. By this means upon holding one of the clutches into contact the beam may be extended into the oven to the desired distance, and upon reversing the clutch it may be withdrawn as far as necessary by reason of the engagement of the pinion 25 in racks 26.

The inner end of the beam is raised and lowered by the rotation of shaft 47, the inner end of which is provided with a bevel-gear 48, in mesh with the upper and lower driving-bevels 49 and 50, loosely mounted on shaft 6 and provided on their inner portions with clutches 51, with which is adapted to engage a vertically-moving clutch 52, in key or spline engagement with the constantly - running shaft 6.

Clutch 52 is normally out of engagement with either clutch 49 or 50 and is raised or lowered by lever 53 engaging in a groove in the clutch, the lever being secured to shaft 54, mounted in bearings in the framework and provided with an operating hand-lever 55, extending upwardly within easy range of the operator. For the purpose of maintaining the lever 53 and clutch 52 in its normal middle inoperative position the shaft 54 is provided with a short arm 56, upon the outer end of which is hung a counterweight 57 by slot 58, elongated downwardly below the end of the arm. The counterweight slightly over-balances the weight of lever 53 and the suspended clutch 52 and rests on the turn-table, as shown. When the clutch is thrown down by the lever, the weight is raised from its bearing, and when the clutch is thrown up the arm passes freely down through slot 58.

Shaft 47 is mounted in suitable bearings, as shown, and is provided at its outer end with a worm 59 in engagement with a similarly-toothed segment 60, pivoted in the bearing-frame at 61 and provided with an extended lever-arm 62. Upward or downward movement of the outer end of the beam is imparted to it through arms 63, pivoted to lever-arm 62, carrying an under roller 65, upon which the beam rests, and by supplemental links 65' an upper roller 66. Links 67, pivoted at 68 in upwardly-extending guiding extensions 69, maintain arms 63 and the supporting-roller 65 in an erect position during the raising and lowering movements of the beam. By these two movements the beam is thrust into or withdrawn from the oven and its operating-head raised or lowered. The movements are ordinarily independent of each other, although when the head is not in engagement with the coke it may be raised or lowered while the beam is traveling longitudinally in or out, the operator having simultaneous control of both levers—i. e., lever 42 in the left hand and lever 55 in the right.

For the purpose of changing the angle of the beam with relation to the main supporting-frame and also to the central line of en-

trance into the oven, so that the sides and front of the oven to the right and left of the door may be reached, I have provided the means for rotating the turn-table and its supported mechanism already described.

The main frame A is supported upon the axles 70, journaled in suitable boxes in the manner of a car, and provided with wheels 71, preferably flanged and adapted to run on the rails 72 of a track which is laid along the front of the ovens sufficiently below the door and adjacent to the front wall to support the machine in proper relation to the ovens.

For the purpose of moving the entire apparatus along the track, either for the purpose of locating it to the right or left of the central position in front of the ovens or for transporting it from one oven to the other, one or more of the axles is positively driven by suitable gearing, and for this purpose I have employed a worm-wheel 73, preferably made in two halves and clamped or otherwise secured upon the axle, into which wheel meshes a worm 74, mounted on the outer end of shaft 75, carried in suitable bearings and provided at its inner end with a bevel gear-wheel 76, intermeshing with oppositely-located driven bevels 77 78, loosely journaled on shaft 5 and provided with friction or other clutch mechanism on their inner surfaces. Between these driving-bevels, in spline engagement with shaft 5, is the movable clutch 79, adapted to be thrown into engagement with either driving-bevel by means of shifting lever 80, pivoted at 81 and connected by pitman 82 with bell-crank lever 83, likewise pivoted at 84 to the upper face of the main frame. The bell-crank lever 83 is provided with upwardly-extending lugs 85, between which pivotally engages the lower end of operating-lever 86, pivotally mounted at 87 in the upper supplemental stationary framework *a* of the machine, the lever extending upwardly within range of the operator, as clearly shown in Figs. 1 and 6, and terminating in a handle 88. The lever 86 is provided with a hand-latch and locking-pawl 89, adapted to engage notches in segment 90 in a manner which will be readily understood. By shifting the lever 86 in either direction either of the clutches may be thrown into engagement and movement will be imparted to shaft 75, resulting in the movement of the entire machine by traction either forward or back, and such movement is accurately controlled by the operator through the means just described. At the side of the machine adjacent to the oven is located the conveyer C, into which the rake-head of the beam draws the coke from the oven. This conveyer consists of a series of slats 91, forming an endless apron passing around and carried by sprocket-wheels 92 and 93 in engagement with sprocket-chains 94, to which the slats are secured in the usual manner. The supporting-framework for the conveyer consists of two longitudinal members, preferably

structural, as T's 95, carrying a pan 96, having upwardly-turned sides, the conveyer framework being carried by brackets 97, secured to and extending outwardly from the main framework, as clearly shown in Figs. 1 and 2. One end of the conveyer C is driven from shaft 5 through sprocket-wheels 98 and chain 99, passing around driven sprocket-wheel 100 on one of the shafts of the conveyer.

The conveyer C receives the coke from the oven and delivers it into the receiving end of the conveyer D, arranged at right angles to conveyer C across the end of the machine and extending outwardly as far as may be desired to deliver the coke into an open-top car or upon the yard. This conveyer is in all respects similar to the conveyer C, consisting of an endless slat belt supported on sprocket-wheels 101 and 102 by shafts mounted on longitudinal framework 103, similar to the other conveyer, the conveyer being driven from shaft 4 through sprocket-wheel 104 and chain 105, passing around driven sprocket-wheel 106, preferably secured to the shaft at the outer end of the conveyer. The conveyer D may, if desired, be inclined so that its outer end will be sufficiently high to drop the coke into an open-top car by gravity.

The operation of the machine will be readily understood from the foregoing description.

The operator stands upon either the revolving platform or turn-table B or upon the upper stationary supplemental part of the main platform *a*, or both, facing the oven-door. All of the levers are within easy reach, so that he can control any of the movements of the machine without changing his position, and it will be seen that the entire apparatus, as to its various movements and operating functions, is within the control of one man.

The machine is very efficient in service, it is capable of cleanly and thoroughly removing the coke in a fraction of the time required by hand, and I have in practice emptied an oven in the most satisfactory manner in eighteen minutes.

The apparatus is not complicated or liable to get out of order, while the coke is delivered without handling directly to the cars and in a better average condition for market than coke drawn by hand.

While the invention shown and described has given satisfactory results in continued use extending over a period of several months and while I have found the details of the apparatus to be efficient and mechanical in their design and operation, it is obvious that variations, changes, and modifications may be made by the skilled mechanic in its various details, design, arrangement, or other particulars, and all such changes and variations are contemplated as within the scope of the following claims.

What I claim is—

1. In a coke-drawing machine provided with

a rake, the combination of a main framework provided with supporting-wheels, a main driving-shaft, a counter-shaft at right angles thereto, a central vertical shaft, and gearing by which movement is transmitted from the main shaft to the counter-shaft and vertical shaft respectively, substantially as set forth.

5 2. In a coke-drawing machine provided with a rake, the combination of a main framework 10 provided with supporting-wheels, a main driving-shaft, a counter-shaft at right angles thereto, a central vertical shaft, gearing by which movement is transmitted from the main shaft to the counter-shaft and vertical shaft 15 respectively, and means for driving one of the supporting-axes and its wheels from the counter-shaft, substantially as set forth.

3. In a coke-drawing machine provided with a rake, the combination of a main framework 20 provided with supporting axles and wheels, a main driving-shaft, a counter-shaft at right angles thereto, a worm-wheel secured to one of the supporting-wheel axles, a driving-shaft provided with a worm in engagement therewith and having a bevel-wheel mounted thereon, oppositely-arranged driving bevel-wheels 25 mounted on the counter-shaft and in engagement therewith, and means for transmitting motion from the counter-shaft to either of 30 said bevel-wheels, substantially as set forth.

4. In a coke-drawing machine provided with a rake, the combination of a main framework provided with supporting axles and wheels, a main driving-shaft, a counter-shaft at right 35 angles thereto, a worm-wheel secured to one of the supporting-wheel axles, a driving-shaft provided with a worm in engagement therewith and having a bevel-wheel mounted thereon, oppositely-arranged driving bevel-wheels 40 loosely mounted on the counter-shaft and provided with clutch mechanism, a sliding clutch mounted on and in engagement with the counter-shaft between said bevel-wheels, and means for shifting the clutch, substantially as set forth.

5. In a coke-drawing machine provided with a rake, the combination of a main framework provided with supporting axles and wheels, a main driving-shaft, a counter-shaft at right 50 angles thereto, a worm-wheel secured to one of the supporting-wheel axles, a driving-shaft provided with a worm in engagement therewith and having a bevel-wheel mounted thereon, oppositely-arranged driving bevel-wheels, 55 loosely mounted on the counter-shaft and provided with clutch mechanism, a sliding clutch mounted on and in engagement with the counter-shaft between said bevel-wheels, a shifting-lever for the clutch, an operating-lever 60 mounted in the framework, and connections between said operating-lever and the clutch-shifting lever, substantially as set forth.

6. In a coke-drawing machine provided with a rake, the combination of a main framework 65 provided with supporting-wheels, a main driving-shaft, a counter-shaft at right angles thereto, a central vertical shaft, gearing by which

movement is transmitted from the main shaft to the counter-shaft and vertical shaft, conveyers located at two adjacent sides of the 70 framework, and driving sprocket-chains therefor connected with driving sprocket-wheels mounted on the outer ends of the main shaft and counter-shaft respectively, substantially as set forth.

7. In a coke-drawing machine provided with a rake, the combination of a main driving-shaft, a counter-shaft at right angles thereto, a turn-table mounted on the main framework, a central vertical shaft, and gearing by which 80 motion is transmitted from the main shaft to the counter-shaft and vertical shaft, substantially as set forth.

8. In a coke-drawing machine, the combination of a main framework provided with 85 supporting-wheels, a main driving-shaft, a counter-shaft at right angles thereto, a central vertical shaft, gearing by which movement is transmitted from the main shaft to the counter-shaft and vertical shaft, a reciprocating beam provided with a rake-head, and means for transmitting movement to the beam in either direction from the vertical shaft, substantially as set forth.

9. In a coke-drawing machine, the combination of a main framework provided with supporting-wheels, a main driving-shaft, a counter-shaft at right angles thereto, a central vertical shaft, gearing by which movement is transmitted from the main shaft to 100 the counter-shaft and vertical shaft, a reciprocating beam provided with a rake-head, an operating-rack secured to the beam, a cross-shaft mounted in bearings upon the table provided with driving-pinions in engagement 105 with the rack, and means for imparting movement to the pinions from the vertical shaft, substantially as set forth.

10. In a coke-drawing machine, the combination of a main framework provided with 110 supporting-wheels, a main driving-shaft, a counter-shaft at right angles thereto, a central vertical shaft, gearing by which movement is transmitted from the main shaft to the counter-shaft and vertical shaft, a reciprocating beam provided with a rake-head, an operating-rack secured to the beam, a cross-shaft mounted in bearings upon the table provided with driving-pinions in engagement 115 with the rack, a driving bevel-wheel on the vertical shaft, driven bevel-wheels loosely mounted on the cross-shaft in engagement with the driving-bevel, and clutch mechanism by which either of said driven bevels is 120 operatively connected with the cross-shaft, substantially as set forth.

11. In a coke-drawing machine, the combination of a main framework provided with supporting-wheels, a main driving-shaft, a counter-shaft at right angles thereto, a central 130 vertical shaft, gearing by which movement is transmitted from the main shaft to the vertical shaft, a reciprocating beam provided with a rake-head, raising and lowering mech-

anism for the beam, a counter-shaft adapted to operate said mechanism, and gearing connecting said counter-shaft to the vertical shaft, substantially as set forth.

5 12. In a coke-drawing machine, the combination of a main framework provided with supporting-wheels, a main driving-shaft, a counter-shaft at right angles thereto, a central vertical shaft, gearing by which movement is transmitted from the main shaft to the vertical shaft, a reciprocating beam provided with a rake-head, raising and lowering mechanism for the beam, a counter-shaft adapted to operate said mechanism and provided with a bevel-wheel mounted thereon, driving bevel-wheels loosely mounted on the vertical shaft and in engagement therewith, and means for imparting movement to either of said bevels from the vertical shaft, substantially as set forth.

15 13. In a coke-drawing machine, the combination of a main framework provided with supporting-wheels, a main driving-shaft, a counter-shaft at right angles thereto, a central vertical shaft, gearing by which movement is transmitted from the main shaft to the vertical shaft, a reciprocating beam provided with a rake-head, raising and lowering mechanism for the beam, a counter-shaft adapted to operate said mechanism and provided with a bevel-wheel mounted thereon, driving bevel-wheels loosely mounted on the vertical shaft and in engagement therewith and provided with clutch devices on their inner sides, a clutch mounted on and in engagement with the vertical shaft between said bevels, and means for shifting the clutch, substantially as set forth.

20 14. In a coke-drawing machine, the combination of a main framework provided with supporting-wheels, a main driving-shaft, a counter-shaft at right angles thereto, a central vertical shaft, gearing by which movement is transmitted from the main shaft to the vertical shaft, a reciprocating beam provided with a rake-head, raising and lowering mechanism for the beam, a counter-shaft adapted to operate said mechanism and provided with a bevel-wheel mounted thereon, driving bevel-wheels loosely mounted on the vertical shaft and in engagement therewith and provided with clutch devices on their inner sides, a clutch mounted on and in engagement with the vertical shaft between said bevels, and an operating-lever in engagement with the clutch, with means for holding it normally in an inoperative position, substantially as set forth.

25 15. In a coke-drawing machine, the combination of a main framework provided with supporting-wheels, a main driving-shaft, a counter-shaft at right angles thereto, a central vertical shaft, gearing by which movement is transmitted from the main shaft to the vertical shaft, a reciprocating beam provided with a rake-head, raising and lowering mechanism for the beam, a counter-shaft

adapted to operate said mechanism and provided with a bevel-wheel mounted thereon, driving bevel-wheels loosely mounted on the vertical shaft and in engagement therewith and provided with clutch devices on their inner sides, a clutch mounted on and in engagement with the vertical shaft between said bevels, an operating-shaft provided with a lever in engagement with the clutch, and a supplemental arm secured to the shaft and in engagement with a slotted counterweight, with means for operating the shaft, substantially as set forth.

30 16. In a coke-drawing machine, the combination of a main framework provided with supporting-wheels, a main driving-shaft, a central vertical shaft, gearing by which movement is transmitted from the main shaft to the vertical shaft, beam raising and lowering means, a toothed segment provided with a lever connected with the supporting means, a counter-shaft provided with a worm-wheel in engagement with the segment, and gearing connecting said counter-shaft to the vertical shaft, substantially as set forth.

35 17. In a coke-drawing machine, the combination of a main framework provided with supporting-wheels, a main driving-shaft, a central vertical shaft, gearing by which movement is transmitted from the main shaft to the vertical shaft, a reciprocating beam provided with a rake-head, raising and lowering mechanism for the beam consisting of supporting means, a toothed segment provided with a lever connected with the supporting means, a counter-shaft having worm-wheel in engagement with the segment and provided with a bevel-wheel, driving-bevels in engagement therewith, loosely mounted on the vertical shaft, and clutch mechanism for imparting movement from the vertical shaft to either of said driving-bevels in either direction, substantially as set forth.

40 18. In a coke-drawing machine, the combination of a main framework provided with supporting-wheels, a main driving-shaft, a central vertical shaft, gearing by which movement is transmitted from the main shaft to the vertical shaft, a reciprocating rake-beam, vertical guides therefor, raising and lowering mechanism for the beam consisting of supporting means, a toothed segment provided with a lever connected with the supporting means, a counter-shaft provided with a worm-wheel in engagement with the segment, and gearing connecting said counter-shaft to the vertical shaft, substantially as set forth.

45 19. In a coke-drawing machine, the combination of a main framework provided with an upper supplemental portion, supporting-wheels, a main driving-shaft, a central vertical shaft, gearing by which motion is transmitted from the main shaft to the vertical shaft, a turn-table constituting a platform mounted on a level with the surface of the upper framework, a reciprocating beam pro-

vided with a rake-head, means for operating the beam, and means for rotating the turn-table, substantially as set forth.

20. In a coke-drawing machine, the combination of a main framework provided with an upper supplemental portion, supporting-wheels, a main driving-shaft, a central vertical shaft, gearing by which motion is transmitted from the main shaft to the vertical shaft, a turn-table constituting a platform mounted on a level with the surface of the upper framework, a reciprocating beam provided with a rake-head, means for raising and lowering the inner end of the beam, means for imparting a reciprocating motion to the beam, and means for rotating the turn-table, substantially as set forth.

21. In a coke-drawing machine, the combination of a main framework provided with supporting-wheels, a main driving-shaft, a counter-shaft, a central vertical shaft, gearing by which motion is transmitted from the main shaft to the counter-shaft and vertical shaft respectively, a turn-table mounted on the upper framework, a reciprocating beam provided with a rake-head, means for operating the beam, a circular rack mounted on the main framework, a toothed wheel in engagement therewith, and means for rotating said wheel from the turn-table, substantially as set forth.

22. In a coke-drawing machine provided with a main framework, and a turn-table mounted thereon, a segmental circularly-arranged toothed rack mounted on the main framework, a toothed pinion in engagement therewith, a shaft carrying said pinion in bearings depending from the turn-table and provided with a worm-wheel, a shaft mounted in the turn-table and provided with a worm in engagement therewith, and means for rotating the shaft, substantially as set forth.

23. In a coke-drawing machine provided with a main framework and a turn-table mounted thereon; a segmental circularly-arranged toothed rack mounted on the main

framework, a toothed pinion in engagement therewith, a shaft carrying said pinion in bearings depending from the turn-table and provided with a worm-wheel, a shaft mounted in the turn-table and provided with a worm in engagement therewith, a hand-wheel mounted on a shaft carrying a driving-bevel, a supporting-framework, and a driven bevel-wheel mounted on the worm-shaft and engaging the driving-bevel, substantially as set forth.

24. In a coke-drawing machine, the combination of a main framework provided with supporting-wheels, a main driving-shaft, a counter-shaft at right angles thereto, a central vertical shaft, gearing by which motion is transmitted from the main shaft to the counter-shaft and vertical shaft respectively, a turn-table mounted on the upper framework, a reciprocating beam provided with a rake-head, means for operating the beam, means for rotating the turn-table, and means for moving the framework along the track, substantially as set forth.

25. In a coke-drawing machine, the combination of a main framework provided with supporting-wheels, a main driving-shaft, a counter-shaft at right angles thereto, a central vertical shaft, gearing by which motion is transmitted from the main shaft to the counter-shaft and vertical shaft, respectively, a turn-table mounted on the upper framework, a reciprocating beam provided with a rake-head, means for transmitting reciprocating motion to the beam from the vertical shaft, means for raising and lowering the end of the beam, means for rotating the turn-table, and means for moving the framework along the track, substantially as set forth.

In testimony whereof I affix my signature in presence of two witnesses.

JOHN A. HEBB.
